RAILWAY BALLAST GRADER

George W. Huey, Frazeysburg, Ohio, assignor of
one-fifth to Louis H. Wise, one-fifth to John R.
Harker, one-fifth to Charles J. Wittlinger, and
one-fifth to George R. Haub, all of Zanesville,
Ohio

Application March 6, 1939, Serial No. 259,995

9 Claims. (Cl. 37—104)

My invention relates to apparatus for removing, cleaning and replacing the ballast of railroad tracks.

One of the methods heretofore employed in the handling and cleaning of ballast consisted in the use of apparatus for pushing the ballast from between the ties to the ends thereof, at the sides of the track, by means of diggers or scrapers, the ballast then being conveyed upwardly and passed over a cleaning screen from whence it was returned to the roadbed.

Another method involved the picking up of ballast from between the ties and the rails, pushing the ballast from the ends of the ties toward the middle of the track, which was also then picked up, the ballast being passed over a cleaning screen and then returned to the roadbed.

The prior apparatus of the first-named type presented difficulty because it extended outwardly past the sides of the track and interfered with the movement of trains on adjacent tracks. In the other type of apparatus the means for picking up the ballast from between the ties was open to the objection that in cases where the ballast was packed tightly by reason of having been in use for a long time and being embedded in dirt, the picking-up members could not function effectively.

My invention has for one of its objects the provision of ballast-removing means which can be operated mainly between the track rails, and which employs conveyer apparatus which will not only dig out and loosen ballast that is compacted between the ties, but which will also effectively cooperate with pushers that move the ballast from the ends of the ties toward the middle of the track, to engage and remove the ballast to screening apparatus, from whence it will be returned to the roadbed.

Another object of my invention is to provide ballast-removing apparatus of such character that the subgrade is given a slope in each direction from the middle of the track towards the ends of the ties, so as to provide for drainage.

In the accompanying drawings, Figure 1 is a side elevational view of a machine embodying my invention; Fig. 2 is a sectional plan view thereof; Fig. 3 is a view taken on the line III—III of Fig. 1; Fig. 4 is a view taken on the line IV—IV of Fig. 1; Fig. 5 is an enlarged view taken on the line V—V of Fig. 1, and showing a portion of the driving mechanism for the conveyers; Fig. 6 is a plan view of the apparatus of Fig. 5; Fig. 7 is a front view showing one of the conveyers; Fig. 8 shows a side view thereof in section; Fig. 9 is a

view taken on the line IX—IX of Fig. 8, and Fig. 10 is a view showing the manner in which the buckets are mounted on the conveyer chains.

The apparatus comprises a carriage which has side frames 12 that carry bearings for a rear axle 13 and a front axle 14, that in turn carry wheels by which the apparatus can be moved along the track rails. Upper frame members 15, 16 and 17 are supported by the side frame members 12.

An engine 18, preferably of the internal combustion type, is mounted upon the truck and provides power not only for traveling movement of the truck along the railroad track, but also serves as a source of power for the moving parts of the mechanism. The motor transmits power through a clutch which is operated by a handle 19. The power shaft of the motor 18 is connected by a coupling member 20 to a driving gear 21 disposed within a speed-reducing housing 22. The gear 21 meshes with a large gear 23 which is provided integrally with a small pinion 24, that meshes with a gear 25. The gear 25 is mounted on a shaft 26, which extends forwardly and is journaled in a bearing 27. A clutch 26a (Fig. 1) is provided for the shaft 26.

Also meshing with the gear 23 is a pinion 28 mounted on a shaft 29 that extends through the housing 22. On the rear of the shaft 29 is a gear 30 which is arranged to be connected and disconnected with the shaft 29 through a clutch mechanism 31. The gear 30 meshes with a gear 32 which is mounted upon a shaft 33 that carries on its inner end a bevel pinion 34 disposed within a transmission unit 35. A shaft 36 is journaled in the transmission housing and slidably carries a pair of bevel gears 37, which through the medium of a shifting fork 38 can be moved to bring either of the bevel gears into mesh with the bevel pinion 34, whereby the shaft 36 can be rotated in opposite directions. Keyed upon the shaft 36 is a high speed gear 39 and a low speed gear 40. A shaft 41 is also journaled in the transmission housing and slidably carries a pair of gears 42 and 43 which may be moved into engagement with the gear 39 and gear 40 respectively. A shifting fork 44 (Fig. 2) is provided, by means of which the gears 42 and 43 may be shifted. The shaft 41 also is suitably journaled in bearings secured to the side frames 12 and carries a gear 45 that meshes with a gear 46 secured to the axle 13.

It will be seen that when it is desired to move the machine along the railroad tracks, with the driving mechanism in neutral position, the opera-

tor will disengage the clutch 31. Also the clutch 26a is disengaged so that the shaft 26 and the mechanism driven thereby, as hereinafter described, will be at rest. Thereupon, by actuating 5 the shifting fork 44, the low speed gear 43 is moved into mesh with the gear 40. Also the shifting lever 38 will be manipulated to move one of the bevel gears 37 into mesh with the pinion 34, depending upon the desired direction of travel 10 of the machine. Whereupon the clutch 31 will be engaged and consequently power will be transmitted to the driving axle 13, through the low speed connections just described. If it is desired to employ the high speed drive, the operator actuates the clutch 31 to break the driving connections, whereupon he will then shift the gear 42 into mesh with the high speed gear 39.

A sprocket wheel is secured to the other end of 20 the shaft 29 and is connected through a chain 47 to a sprocket secured on the shaft of a fluid compressor 48. A storage tank 49 is provided in conjunction with the compressor 48.

A U-shaped frame or beam 50 is pivotally connected at 51 to the upright frame members 15, and pivotally carries at its forward end hanger plates 52. The plates 52 support a pair of cross beams 53 that constitute a part of the conveyer frame. A pair of cross beams 54 is suspended 30 from the beams 53 by means of a pair of conveyer-supporting beams, indicated generally by the numeral 55 (Fig. 8).

As shown more clearly in Figs. 7, 8 and 9, each conveyer-supporting beam 55 consists of a square 35 tube 56, which at its upper end is provided with a pair of plates 57 through which extends a shaft 58, to which is secured a sprocket wheel 59. At opposite sides of the member 56 are disposed channels 60 that are connected together by bolts 40 61 which extend through elongated slots in the member 56. Connecting bolts 62 extend through the beams 53, through elongated slots in the members 60, and through the member 56. Similarly, connecting bolts 63 extend through the 45 members 54, 56 and 60. A sprocket wheel 64 is mounted upon a shaft 65 that is carried by the lower ends of the channels 60.

The member 56 carries a cross bar 66 which extends through elongated slots in the members 50 60. Each of the channels 60 is provided with a pair of lugs 67 disposed at opposite sides of the cross member 66, and adjusting bolts 68, having screw threaded engagement with the lugs 67, have their extremities in clamping engagement 55 with the cross member 66. It will be seen that upon loosening of the through bolts 62 and 63, and the bolts 61, the adjusting screws 68 can be manipulated in order to effect movement of the member 56 relative to the channels 60, thus effecting elongation or shortening of the conveyer beam 55. The flanges of the members 60 serve 60 as tracks for the conveyer buckets, to be hereinafter described.

A conveyer chain 70 passes around each pair of 65 sprockets 59-64, the chains carrying conveyer buckets 71 that are connected to the chain through brackets 72 which are connected to the chain links by pivots 73. The buckets carry digger teeth 74 for loosening and digging into the ballast so that it can be scooped into the buckets. The brackets 72 carry rollers 75 which roll along the track members 60. At their lower ends, the track members 60 are enlarged to arcuate shape to form cam surfaces 76, to effect tilting or swinging 70 of the buckets as they pass around the lower

sprockets 64, the digger teeth of the buckets being initially moved perpendicularly into the ballast and the buckets then being swung about their pivotal connections 73 and then moved in an arcuate path through the ballast as they pass around the lower sprocket wheels 64. The buckets are held in an upright position during upward travel until the rollers 75 pass off the upper ends of the track members 60, whereupon the weight of the ballast in the buckets will cause the buckets to tilt and discharge the ballast into chutes 77. Continued upward movement of the buckets will bring the rollers 75 into engagement with cam segments 78 that are carried by the arms 57. The buckets are thereby brought again into alignment with the conveyer chains. As shown more clearly in Fig. 3, there are a pair of conveyers that discharge into the chutes 77 which are carried by the cross bar 53 at the sides of the machine.

The shafts 58 are supported in bearing brackets 80 that are supported upon the cross beams 53. One of the shafts 58 carries a sprocket wheel 81 and the other shaft carries a sprocket wheel 82. Pairs of hanger bars 83 and 84 are carried by the shaft 58 and have shafts 85 and 86, respectively, journalled in their lower ends (Fig. 5). The shaft 85 carries a sprocket 87, and a chain 88 passes around the sprockets 87 and 81. A sprocket wheel 89 is secured to the shaft 86, and a sprocket chain 90 passes around the sprocket 89 and the sprocket 82. The shafts 85 and 86 respectively, carry sprocket wheels 91 and 92 which are driven by sprocket chains 93 and 94 respectively, the chains 93 and 94 being in turn driven from the sprocket wheels 95 and 96 respectively. The sprocket wheel 96 is carried by the shaft 26, while the sprocket wheel 95 is carried by a shaft 97. A gear wheel 98 on the shaft 26 meshes with a gear wheel 99 on the shaft 97, so that the shaft 26 will drive the sprocket chain 90 in a counter-clockwise direction and the sprocket chain 88 in a clockwise direction, as viewed in Figs. 3 and 5.

The shaft 97 is journalled in spreader bars 101 which are supported by the shaft 26, while the bearing 27 of the shaft 26 is supported upon a stationary cross bar 102, constituting a part of the machine frame. The shaft 86 is similarly supported by a pair of spreader bars 101a.

A bracket 103 is rigidly mounted on the cross member 102, and pivotally supports a vertically-disposed cylinder 104, as shown more clearly in Fig. 1. A piston within the cylinder 104 is pivotally connected to a cross bar 105 that is carried by the U-frame 50. Fluid pressure for actuating the piston is supplied from a pump 106, and oil may suitably be employed as a motive fluid. The pump is driven through a sprocket chain drive 107 (Fig. 2), and a shaft 108 having a gear wheel 109 that meshes with the gear wheel 21. It will be understood that the pump 106 may be of standard form, having a suitable by-pass relief to prevent building up of excessive pressure.

A valve 110 (Fig. 1) is provided for controlling the admission and exhaust of fluid at the lower end of the cylinder 104. It will be understood that when fluid pressure is admitted to the lower end of the cylinder, the beam 50 will be swung upwardly about its shaft 51, thus raising the beams 53 and 54 and the parts carried thereby including the conveyers and their drive chains. Vertical movements of the conveyer frame will not interfere with the driving connections shown on Fig. 5, because while the shaft 26 is jour-

nalled in a stationary bearing, the spreader bars 101 and 101a, and the members carried thereby swing about the shaft 26 as an axis. When moving from only one tie space to another tie space, the conveyer frame need not be lifted so high as when traveling. It will be understood that when the conveyer frame is in its lowermost position, the conveyer buckets will engage the ballast between the ties. The conveyer frame is guided in its vertical movements by guide blocks 111 that are secured to the beams 53 and 54 and have slidale engagement with vertical flanges formed on the upright truck frame members 17.

Pairs of brackets 112 are mounted upon the ends of the beams 53. A cylinder 113 is pivotally connected at 114 to each pair of brackets and contains a piston having a piston rod 115 connected to legs 116 of a bell crank, the bell crank being pivotally connected at 117 to the cross beams 54. The legs 118 of the bell crank carry pins 119 which extend through cam slots 120 that are formed in links 121, which are pivotally supported upon brackets 122 that are secured to the cross beams 54. The lower ends of the links 121 are pivotally connected to arms 123 of pushers 124. The arms 123 are pivotally supported by hangers or links 125 from the cross beam 53.

It will be understood that since the pushers are carried by the cross beams 53 and 54, they will be brought to operative position on the roadbed when the conveyer frame is lowered, the normal position of the pushers being indicated by the broken lines in Fig. 3. Upon admission of fluid pressure from the pump 106 to the upper ends of the cylinders 113, the bell cranks 116-118 will be moved in a clockwise direction to swing the pushers 124 from their dotted line positions to their full line positions, thus moving ballast from the ends of the ties toward the middle of the track. This inward movement of the pushers is along an inclined plane, which slopes from the middle of the track toward the sides thereof, so that there will be drainage of the roadbed from the middle toward the sides thereof. This movement is accomplished by tilting of the pushers 123 on their supporting links 125. This tilting movement is effected by reason of the fact that the links 121 are of shorter radius than the links 125, and the relative positions of the axes of the links 121 and 125 are such as to effect the tilting of the pushers as above referred to. Ordinarily the buckets will first be caused to remove the ballast at the middle of the track, whereupon fluid pressure will be admitted to the cylinders 113 to effect movement of the pushers from their dotted line positions in Fig. 3 to their full line positions. In their latter-named positions, they will assist in directing the ballast into the conveyer buckets.

It will be understood that the buckets of each conveyer are staggered longitudinally of their chains relative to the buckets on the other chain, so that the buckets can engage the material in the middle of the track without the buckets of one conveyer interfering with the buckets of the other conveyer.

Counterbalancing springs may be employed for connecting the beam 50 to the truck frame, to prevent too abrupt downward movement of the conveyer frame, or exhaust of fluid from the cylinder 104 can be retarded in a suitable manner, as by not opening the valve 110 to its fullest extent.

The material removed from between the ties and deposited within the chutes 77 flows down-

wardly into a trough 130 which is pivotally supported at 131 upon bracket arms 132 secured to the frame members 17. An arm 133 extends rearwardly from the hopper 130 and is pivotally connected to a link 134 that is in turn connected to a link 135. One end of the link 135 is pivotally connected at 136 to the casing 22. The other end of the link 135 has pivotal connection with a rod 137 that has eccentric connection with the shaft 108, so that as the shaft rotates, the trough 130 will be vibrated vertically.

The material from the chute 77 drops onto screens 140 in the ends of the trough, and since the screens slope rearwardly and inwardly, the ballast will be directed toward the middle of the trough, the cinders and dirt being sifted out and passing downwardly through spouts 141. The transverse portion 142 of the trough slopes downwardly to an opening 143 through the bottom of the trough, and through this opening the ballast is discharged into a spout 144, from whence it falls to the roadbed behind the point at which other material is being removed for cleaning. Since the portion 142 of the trough is of narrower dimension relative to the screens, the material has to pass entirely over the screens before it can enter the intermediate portion of the trough.

The material which passes through the spout 141 falls upon a transverse belt conveyor 146, by which it is discharged across a chute 147 to the side of the track. The belt 146 passes around drums journaled in bracket plates 148 which extend transversely of and are carried by the truck frame. The drum at the discharge end of the conveyor is mounted on a shaft 150 which carries a sprocket wheel 149. A chain 151 passes around the sprocket wheel and around a sprocket wheel 152, the sprocket 152 being mounted on a shaft which also carries a sprocket 153, around which a chain 154 passes, the chain also passing around a sprocket on the shaft 26.

The chute 147 is journaled on the shaft 150 and can be raised by a rope 155 to permit travel of the truck.

The operator will ordinarily stand on a platform 157 at the front of the machine, and through suitable levers or pull rods, will operate the various clutch levers and valves for the cylinders above referred to.

In some instances the ballast and dirt will be so tightly packed or frozen that the buckets will not readily penetrate and dislodge the same, and I therefore provide a row of pneumatic hammers 158 on the platform 157 to effect preliminary loosening of the ballast. The compressed air for these hammers is supplied from the reservoir 49. The compressor 48 will also be utilized for supplying air to brake cylinders 160.

I claim as my invention:

1. Apparatus for removing ballast from railroad tracks, comprising a supporting structure, a pair of endless conveyers carried by said structure, and movable between the ties and between the rails, in a common vertical plane disposed transversely of the track, and means for pushing ballast from points adjacent to the ends of the ties into the path of the conveyers and guiding it into the conveyers.

2. Apparatus for removing ballast from railroad tracks, comprising a supporting structure, a pair of endless conveyers carried by said structure, and movable between the ties and between the rails, in a common vertical plane disposed transversely of the track, and means for pushing ballast into the path of the conveyers.

- last from points adjacent to the ends of the ties into the path of the conveyers and supporting the ballast against displacement from said path, the adjacent runs of the conveyers moving in a downward direction.
5. Apparatus for removing ballast from railroad tracks, comprising a supporting structure, a pair of endless conveyers carried by said structure, and movable in a common vertical plane disposed transversely of the track, means for pushing ballast from points adjacent to the ends of the ties into the path of the conveyers, the adjacent runs of the conveyers moving in a downward direction, and each conveyer having buckets staggered relative to the buckets on the other conveyer, whereby portions of the buckets on both conveyers can move through a common path.
4. The combination with means for removing ballast from a road bed, of a pusher device movable from one side of the roadbed toward the longitudinal center line thereof, and means for moving said device along an approximately straight path, in a plane which slopes upwardly from the edge of the track toward the middle thereof.
5. The combination with means for removing ballast from between the ties of a railroad track, at points between the rails, of pusher devices for removing ballast from points adjacent to the ties toward the said removing means, and means for moving the pusher devices in upwardly inclined planes from points beyond the ends of the ties toward the middle of the track, whereby the roadbed is given a slope to the sides of the track.
6. Apparatus for removing ballast from between the ties of railroad tracks, comprising a main supporting frame, an auxiliary frame carried thereby, conveyers mounted on the auxiliary frame in position to be moved between the cross ties of the track, pusher members carried by the auxiliary frame in position to engage material

adjacent to the edges of the track, means for raising and lowering the auxiliary frame, and means for moving the pushers toward the conveyor to move ballast into the path of said conveyer.

5

7. Apparatus for removing ballast from between the ties of railroad tracks, comprising a main supporting frame, an auxiliary frame carried thereby, a pair of conveyers mounted on the auxiliary frame in position to be moved between the cross ties of the track, pusher members carried by the auxiliary frame in position to engage material adjacent to the edges of the track, means for raising and lowering the auxiliary frame, and means for moving the pushers toward the conveyor to move ballast into the path of said conveyer, each conveyer moving in a direction opposite to the movement of an adjacent pusher while receiving a load of the ballast.

15

8. Apparatus for removing ballast from railroad tracks, comprising a pusher, means for advancing the pusher from a point adjacent to one end of the cross ties and between two cross ties, toward the middle of the track, in a direction generally parallel to the cross ties, a ballast receptacle, means for moving the receptacle in a direction opposed to the said movement of the pusher, for the purpose of receiving the ballast from the pusher when the pusher is in its advanced position, and means for raising the receptacle.

20

9. Apparatus for removing ballast from railroad tracks, comprising a pair of pushers, means for advancing the pushers from opposite ends of a cross tie toward the middle of the track, ballast receptacles, means for moving said receptacles to points between adjacent cross ties, and each towards one of the pushers, for receiving ballast from the pushers when the pushers are in advanced positions, and means for raising the receptacles.
